UNITED STATES PATENT OFFICE.

HERMAN GEORG WEIBEZAHL, OF NEW YORK, N. Y.

PLIERS OR KINDRED TOOL.

SPECIFICATION forming part of Letters Patent No. 681,160, dated August 20, 1901.

Application filed January 9, 1901. Serial No. 42,653. (No model.)

To all whom it may concern:

Be it known that I, HERMAN GEORG WEIBEZAHL, a citizen of the United States, and a resident of the borough of Manhattan, city, county, and State of New York, have invented 5 certain new and useful Improvements in Pliers or Kindred Tools, of which the following is a specification.

The object of my invention is to provide a 10 portable tool of convenient size and form and possessing great capacity for a variety of useful work. It involves a combination of one or more pairs of parallel-moving sets of jaws 15 operated simultaneously by the same movement of the handles through a combination of compound leverages, single or duplex, my primary power being derived through two independent levers, each working on its own fulcrum, which is movable and pivoted to 20 its load, which also is movable, with the fulcrums approaching the loads and the levers relatively lengthening as the jaws approach each other—that is to say, the nearer the tool 25 is closed the closer are the fulcrums to the load and the longer become the levers, with the result that as the need for power increases 30 it is automatically supplied. A secondary system of levers is used through which the power is communicated and which assist in drawing the various jaws toward each other and insure the parallel position of all the jaws.

I have adapted the tool for single compound leverage and for duplex compound leverage, each having the principles above outlined in 35 its construction.

I will first describe what I consider the best form of my invention—that with the duplex compound leverage—and will afterward indicate certain important modifications.

40 The accompanying drawings form part of this specification and represent what I consider the best means of carrying out the invention.

Figure 1 is a general face view of the tool 45 when open with the secondary levers on the near side omitted. Fig. 2 is a similar view of the tool complete when closed. Figs. 3 and 4 are portions of the tool, showing in detail the construction of those parts. Fig. 5 is an 50 edge view of the tool closed. Fig. 6 is a partial vertical section of another form of my improved tool having two pairs of jaws. Fig. 7

is still another form of my invention, showing the same in an open position. In this view the secondary levers on the near face 55 are omitted. Fig. 8 is a view of the tool shown in Fig. 7, the same being illustrated as closed. Fig. 9 is a general face view of a modification employing the single compound lever-age. The auxiliary levers on the near side 60 are omitted.

Similar letters of reference indicate corresponding parts in all the figures where they appear.

I have shown the end carrying the terminal 65 jaws as the upper end and may refer to it as such, although it will be understood that the tool may be worked in all positions.

Referring to Fig. 1, A B are the primary levers, crossing each other and pivoted to the 70 slides carrying the side jaws. I will describe them separately.

The lever A is bifurcated, each of the tines extending over the corresponding tines of the lever B. Pivotal pins A' connect the tines of 75 the lever A with a lip G' on each side of the slide G, the terminals of the tines being recessed in said slide on its outer faces. A slot is provided at a, in which works a rivet D², which constitutes the connection between 80 this lever and the secondary levers D D and the tongue F³.

B is the opposite lever. It is slotted at b, in which slot works the rivet C², which constitutes its fulcrum and connects it with the 85 secondary levers C C and the tongue E³. It is pivoted by the pin B' to the slide H, being set between the lips H' on said slide and the tongue F³. This lever is also bifurcated, but made narrower than its mate, so that its 90 tines will work easily between those of the lever A. Although in contact with each other, the levers A B are not directly connected with one another, but are independent.

The secondary levers are four plates, two 95 on each face of the tool and working in pairs. C D represent one pair. Another pair, similarly lettered, is mounted on the near face. The back pair is shown in Fig. 1 and the front pair in Fig. 2. I may mount them corre- 100 spondingly, as shown in Figs. 7 and 8, or each pair in reverse relation to each other, as shown in Figs. 1, 2, and 5. All four are of moderate thickness, but wide, and are joined at

their centers by a rivet W. Each of these levers has a wing extending laterally near its mid-length, each lever therefore having three terminals. Each terminal carries one end of a terminal rivet, which, extending through to the opposite side of the tool, stiffly connects the front and back levers at those points. The rivet C² connects the lower terminals of the two levers C and passes through the tongue E³, to be presently described, and through both tines of the primary lever B in the slot at b. The pin or rivet D² performs similar functions in the corresponding opposite parts. The pin C' connects the upper extremities of both levers C, passing through F in the slot at f. The pin D' connects the upper extremities of the levers D D, working in the slot e. In the lateral wings or arms C³ of the levers C C is a slot at c, in which works the pin H³, hereinafter described. In the slot at d the pin G³ similarly connects the arms of the levers D D. The two pairs of levers C D D C revolve freely upon the rivet W, which joins them to each other. In order to make the various terminals of each pair occupy the same plane on their respective sides of the tool, I overlay the various terminals of the outer plates with sections of metal of the same thickness, as indicated by X in Fig. 5.

E is the portion of the tool carrying one member, E', of the upper pair of jaws and one member, E², of the corresponding pair of side jaws. A tongue E³ extends downward parallel to the face of the jaw E' and carries the slide G, before referred to. I provide an upright slot at e, in which works the pin or rivet D'. The rivet C² extends through the lower end of the tongue E³, as before mentioned. E⁴ represents small teeth formed on a portion of the inner face of the tongue E³.

F is a counterpart to the member E. It has the jaws F' F² and the tongue F³, equipped with fine teeth F⁴. It is slotted at f and receives the rivet C'. The rivet D², which has been heretofore referred to as the fulcrum of the lever A, extends through the lower end of the tongue F³.

The slide G is matched upon the tongue E³, upon which it easily moves upward or downward. It has the jaw G², formed to match that of the corresponding jaw E², and has lips G', which engage with the lever A by a smoothly-rounded surface, to be again referred to. The parts are held together by the rivet A'. The pin G³ extends through the slide G, working in the slots d in the lateral wings of the secondary levers D. Another hole to receive this pin is provided at g, so that the extent of closing the side jaws may be altered by a change of position of the pin from one hole to the other.

G⁴ is a rack recessed into the slide G, which rack is equipped with teeth designed to mesh into the corresponding teeth E⁴ on the tongue. It is pivoted at G⁶, so as to allow it to swing inward to a limited extent only, be-

ing arrested by its inner recess, and is pressed inward by a spring G⁵. The uses of this rack will be set forth hereinafter.

H is a slide arranged in the reverse position to the slide G and is similar thereto, except that whereas the lips G' lie close to the corresponding tongue E³ and allow the rivets A' to extend outward and receive the lever A on their outer face the lips H' lie sufficiently away from the corresponding tongue F³ to receive the terminals of the lever B on their inner faces between the lips and the tongue, the rivet B' extending inward from the lips H' to form the necessary strong engagement with the operating-lever B.

I and J are springs urging the levers A B apart.

In the operation of the tool as the primary levers A B are pressed together, being pivoted on the slides G and H and working over the independent fulcrums C² D², the latter are forced toward each other. As these carry the secondary levers C D and the members E F, the various jaws consequently all approach each other, the slots in the upper portions of E and F allowing the upper terminals of the secondary levers to move upward. The primary levers A B, working over their respective fulcrums, lift upward the slides G and H with great force by means of their terminals. The slots c d in the lateral terminals of the secondary levers, in which slide the pins G³ H³, regulate the upward movement of the slides and give the latter uniformity of action, assisting also in their movement to powerfully close the side jaws E² G² F² H² or to partially close the same, according as the pins G³ H³ are set in one or another of the holes in their respective slides. As the pins C² D², constituting the fulcrums of the primary levers, travel toward each other and upward in the slots b a the distance between the fulcrums and the load is decreased, while by the same change the handles of the primary levers are lengthened and a constantly-increasing power is obtained as the need for same grows greater.

While this combination of leverages gives a motion and action to the side jaws analogous to that commonly known as the "toggle-joint," the movement of the jaws as they close decreasing very largely near the termination of the closing movement as compared to the motion of the operating-levers, and therefore gaining greatly in force, the movement also resembles the spiral. The portion of the circle described by the upper extremities of the levers A B is a constantly-decreasing one, the fulcrums being taken as the center, and the lower extremities of the levers describe a proportionately-increasing radius as the tool is closing. The result of this movement is that the nearer the tool is closed the more directly above the levers comes the load and the more powerfully are the jaws made to act.

It will also be seen that as the tool closes the secondary levers are forced toward the upper terminals

of the end jaws, lessening the strain on those jaws and strengthening their gripping power, transferring the strain to the tongues. A greater resistance-power is also given there-
5 by to the jaws $E^2 F^2$, the rising of the pins in the slots increasing the hypotenuse of a triangle formed by the slots $e f$ acting as the perpendiculars and the jaws $E^2 F^2$ as the base.

The upper ends of the primary levers are 10 finished to present a portion of a circle and conform exactly to circular recesses made in the slides $G H$. The surfaces fit each other closely. This relieves the pins $A' B'$ from strain and also relieves the pins $G^3 H^3$, working in the slots at $c d$ in the lateral terminals 15 of the secondary levers, making the tool not only one of extraordinary power and capacity, but also one of great durability, every part helping to support the other no matter at 20 what point the pressure is sustained.

I employ the toothed racks $G^4 H^4$ to lock the tool and relieve the hands after the object to be manipulated has been firmly grasped. The operating of the tool tends to bring the 25 racks $G^4 H^4$ into contact with the corresponding toothed surfaces at $E^4 F^4$ through the inwardly-pulling strain exerted upon the slides $G H$ by the primary levers $A B$, owing to any slight natural side play in the slides upon 30 their tongues, the latter being made slightly narrower than the matched holes through the slides which work upon said tongues. As the slides move upward the racks ride over the teeth $E^4 F^4$ until one of the sets of jaws 35 comes into contact with the object to be grasped, when the teeth become firmly locked and remain so until the handles are allowed to open, when the outward push of the levers upon the slides tilts these strongly upward 40 and throws the racks and teeth apart. In opening the tool the racks are always removed from the toothed surfaces sufficiently through the tilting of the slides to make their engagement impossible. The gripping of an object 45 with parallel surfaces by one pair of the side jaws will of course prevent the rack on that particular slide from firmly engaging with the corresponding toothed surface, but the tool will be held by the other rack and corre- 50 sponding teeth. When the strain comes upon the end jaws, both racks will be engaged.

Fig. 9 is a modification employing single compound leverage. Its parts correspond to portions of the duplex described above, except that only one of the handles turns. It is a simpler tool and may be made cheaper, while giving a good part of the same advantages. In this Fig. 9 the primary lever A^8 instead of being pivoted to a lip or lug E^8 , as 55 shown, may extend farther, exactly as the corresponding part is shown in Fig. 1, and be similarly connected to the slide on the left side of the figure. I prefer the form shown in Fig. 1.

55 Other modifications may be made without departing from the principle or sacrificing the advantages of my invention, such as bend-

ing the terminals of the secondary levers so as to have them occupy the same plane, as indicated by Y in Fig. 8. I can make the 70 parts $G^4 H^4$ and $E^4 F^4$ slightly roughened or corrugated or make the parts $G^4 H^4$ with but one tooth instead of a series. I may reverse the position of various parts also.

The three sets of jaws each working parallel 75 enables me to put the tool to a variety of uses. While I have designated it as pliers and kindred tools, it may be made use of in various ways. Its great power and the engagement of the teeth when in use automatically make it especially adapted to apply to a wrench, nippers, cutters, gas-pliers, and a variety of other opening and closing devices for various purposes or for a combination of 80 various tools.

85 Parts of the construction shown may be used without others. I may employ only one pair of side jaws, as shown by $E^{10} G^{10}$ in Fig. 6, the provision for the sliding connection with the tongue F^{10} of the opposite end jaw F^X being established by a rivet B' engaging the ends of the tines of the primary lever B^X and playing in the slot F^Y . When I use only a pair of end jaws, as indicated by $E^{11} F^{11}$ in Figs. 7 and 8, then the sliding provision with 90 both tongues $E^{12} F^{12}$ of said jaws is established by rivets $A^{11} B^{11}$ engaging with the ends of the tines of the primary levers $A^{12} B^{12}$ and playing in slots $E^{13} F^{13}$. By these arrangements I thus retain all the features of the 95 powerful leverage of the tool, although employing but one or two sets of jaws.

Having now fully described my invention, what I claim is—

1. In a pair of pliers, end jaws in combination with side jaws, equipped to insure parallel movements of each set, and with a single pair of operating-handles, all arranged for joint operation substantially as herein specified.

110 2. In a pair of pliers, end jaws in combination with side jaws all equipped to insure parallel movements, and with a single pair of operating-handles, slotted and crossed, all arranged to serve substantially as herein specified.

115 3. In a pair of pliers, end jaws in combination with side jaws, carried on slides, all equipped to insure parallel movements, and with a single pair of operating-handles, slotted and crossed, with circular bearings at the operating ends of the handles and corresponding recesses in the slides, all arranged for joint operation, substantially as herein specified.

120 4. A pair of pliers having a plurality of parallel-moving jaws actuated by two sets of levers, the primary set, serving as handles, being independent of each other and working on independent movable fulcrums, substantially as herein specified.

125 5. In a pair of pliers with parallel-moving jaws actuated by two sets of levers, the primary set independent of each other, working

on independent movable fulcrums, with a secondary set of levers working in slots in the portions carrying the end jaws and rising in said slots as the tool is closed, all substantially as herein specified.

6. In a pair of pliers, end jaws and side jaws, each pair of jaws having parallel motions, in combination with secondary levers having side wings, mechanical connection between such wings and side jaws, and a single pair of operating-handles, all arranged substantially as herein specified.

7. In a pair of pliers, end jaws and side jaws, each pair of jaws having parallel motions, in combination with secondary levers having side wings, mechanical connection between such wings and side jaws, and provisions for changing the adjustment of such connections so as to vary the opening of the side jaws relatively to the end jaws, all substantially as herein specified.

8. A pair of pliers having parallel-moving jaws actuated by two sets of levers, the primary levers fastened to movable centers, and working on movable fulcrums, arranged to automatically shift the fulcrums and increase the length of the levers, adapted to serve substantially as herein specified.

9. In a pair of pliers having parallel-moving jaws, the combination of movable ful-

crums and centers and variable levers with secondary levers with lateral terminals, slotted, such secondary levers being engaged through slots at one terminal and pivoted at the other terminals by means of pins $C^2 D^2$, 35 combined as shown, so that each of said pins performs the triple functions of a fulcrum for a primary lever, a pivot for two secondary levers and a means for controlling directly a tongue of the parallel end jaws, all 40 adapted to serve substantially as herein specified.

10. In a pair of pliers having parallel-moving jaws, moving centers, shifting fulcrums and variable primary levers working in conjunction with sets of secondary levers, of toothed racks and corresponding toothed surfaces, arranged to mesh automatically when the jaws come into action, and to disengage automatically upon the opening of the handles, all adapted to serve substantially as herein specified.

Signed at New York, in the county of New York and State of New York, this 31st day of December, A. D. 1900.

HERMAN GEORG WEIBEZAHL.
